UNITED STATES PATENT OFFICE.

LOUIS HUENKE, OF NEW BREMEN, OHIO.

WHEEL-OPERATED REIN-HOLDER.

SPECIFICATION forming part of Letters Patent No. 716,233, dated December 16, 1902.

Application filed November 15, 1902. Serial No. 131,504. (No model.)

To all whom it may concern:

Be it known that I, LOUIS HUENKE, a citizen of the United States, residing at New Bremen, in the county of Auglaize and State of Ohio, have invented certain new and useful Improvements in Wheel-Operated Rein-Holders; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention has relation to improvements in rein-holders of that kind or style operated by the wheel of the vehicle; and the object is to provide a device of the kind named attachable to a wheel of a vehicle and operated thereby which is simple in construction, certain and efficient in operation and results, and which is strong and durable.

The invention embodies a flanged ring-plate to fit over the hub of the wheel and formed 25 with an annular flange about the hub-opening, a disk-ring revolvably posited in the circular channel between the inner and outer flanges, means to lock the disk-ring against rotation in one direction, and rein-holders 30 fixed in the disk-ring.

The invention therefore consists in the novel construction of parts and their aggroupment in operative combinations, as will be hereinafter fully specified, and the novelty 35 claimed particularly and distinctly pointed out.

I have fully and clearly illustrated the invention in the accompanying drawings, to be taken as a part hereof, and wherein—

40 Figure 1 is an elevation of a vehicle-wheel having my improved rein-holder applied thereto and showing the vehicle-body in relation thereto. Fig. 2 is a front view in elevation of the rein-holder. Fig. 3 is a side view of the wheel-hub, the spokes being shown as broken off, the rein-holder as mounted on the outer portion of the hub, and a means for holding the rein-holder in position. Fig. 4 is a transverse section through the device. 45 Fig. 5 is a fragmentary plan view of the base flanged ring, showing the locking grooves or recesses therein.

In the drawings similar reference-notations designate the same parts appearing in the several illustrations.

55 Referring to the drawings, A designates a vehicle-wheel of any approved construction or make adapted to have mounted on the outer portion of the hub my improved rein-holder, substantially as shown in the drawings in Fig. 3.

1 designates a plate-ring or disk having an annular rim-flange 2, a central opening to fit over the hub, and an annular flange 3 about the opening, as shown in the drawings. It 65 will be perceived that this construction provides a circular channel between the rim-flange and the flange around the central opening. In the floor of the circular channel are made inclined locking-seats 4, ending 70 in a vertical wall 5 and curved in their approaches concentric with the axis of the ring or disk. In the circular channel is revolvably posited a plate-ring 6, which is held in relative position by a flat ring or washer 7, 75 secured on the face of the flange 3 and lapsing over the face of the revolvable plate-ring 6, as indicated in the drawings.

In the revolvable ring 6 is secured a hollow sleeve 8, wherein is rotatively journaled the 80 stem 9 of the rein-holder 10, the inner end of the stem being headed, as shown, to prevent its lengthwise movement. The rein-holder 10 consists of triplicate prongs or arms, as shown, in order that the lines or reins may 85 be arranged therein conveniently and always be engaged by two of the arms so they will be kinked, wrapped, and locked against withdrawal.

90 Diametrically opposite to the sleeve 8 is secured another sleeve 11, having a rigid arm 12. Loosely arranged in the inner portion of the sleeve 11 and projecting through the ring 6 is a locking-pin 13, between the outer end of which and the inner end of the arm 12 is 95 placed an expansive spring 14, so that the inner end of the locking-pin is always made to ride on the floor of the main ring and automatically engage in the inclined recesses and also lodge against the end walls thereof and 100 lock the ring against reverse movement.

The device is secured to the hub of the right-hand wheel of the vehicle by slipping it over the hub until it lodges against one of

the shoulders thereon, and then clips 15, suitably secured to the main ring-plate, are clamped to the base of oppositely radial spokes, as shown in the drawings in Fig. 3.

5 In the utilization of the device the reins or lines are disposed in the three-prong holder and then carried over and around the pin of the other holder to keep them from slipping. Then, it will be perceived, should the wheel 10 be turned reverse to the direction of forward movement it will automatically be locked against such motion by the engagement of the locking-pin against the end wall of the recesses, and should the movement be in forward direction the lines will be tightened, and that the more pronounced the forward movement the resistance will be applied with increasing power.

Having thus described my improvements, 20 what I claim, and desire to secure by Letters Patent, is—

1. A wheel rein-holder comprising a plate-ring formed with a rim-flange and a central opening having an annular flange around it 25 and inclined locking-recesses in the floor of the ring, a ring revolubly posited between said flanges, a washer secured to the annular flange and lapped over the revoluble ring, a sleeve fixed in the revoluble ring, a pronged rein-holder having a stem journaled in the sleeve, a fixed rein-holder having a hollow base and secured to the revoluble ring opposite to the pronged rein-holder, a locking-pin slidably disposed in the hollow base of the rein-pin and passing through the revoluble ring, and an expansive spring arranged between the adjacent ends of the rein-pin and the locking-pin.

rotatable rein-holder journaled in the revoluble ring, a fixed rein-pin secured in the ring 30 directly opposite to the rein-holder, and a locking-pin between the rings to engage the locking-recesses in the plate-ring.

2. A wheel rein-holder comprising a plate-ring formed with a rim-flange and a central 35 opening having an annular flange around it and inclined locking-recesses in the floor of the ring, a ring revolubly posited between said flanges, a washer secured to the annular flange and lapped over the revoluble ring, a sleeve 40 fixed in the revoluble ring, a pronged rein-holder having a stem journaled in the sleeve, a fixed rein-holder having a hollow base and secured to the revoluble ring opposite to the pronged rein-holder, a locking-pin slidably 45 disposed in the hollow base of the rein-pin and passing through the revoluble ring, and an expansive spring arranged between the adjacent ends of the rein-pin and the locking-pin.

In testimony whereof I affix my signature in presence of two witnesses.

LOUIS HUENKE.
